UNITED STATES PATENT AND TRADEMARK OFFICE
CERTIFICATE OF CORRECTION

PATENT NO. : Des. 395,158
DATED : June 16, 1998
INVENTOR(S) : Glenn Lindaman

It is certified that error appears in the above-identified patent and that said Letters Patent is hereby corrected as shown below:

On the title page, item [22]:

The filing date at [22] is February 21, 1998, not February 19, 1998.

Insert before the Claim: -- The broken line showing of the human form in Figure 1 and 2 is for illustrative purposes only and forms no part of the claimed design. --

In Fig. 1, after the word "with", delete "a receptacle for shin guard" and substitute therefor --ankle strap--.
